(57) **CLAIM**

The ornamental design for a basket sponge holder, as shown and described.

DESCRIPTION

FIG. 1 is a front elevation view of a basket sponge holder showing our new design;

FIG. 2 is a rear elevation view thereof;

FIG. 3 is a top plan view thereof;

FIG. 4 is a bottom plan view thereof;

FIG. 5 is a right side elevation view thereof, the left side elevation being the mirror image thereof;

FIG. 6 is a bottom, front perspective view thereof; and,

FIG. 7 is a bottom, rear perspective view thereof.

The material shown in broken lines in FIG. 1 does not form a part of the claimed invention.
